SPOON OR SIMILAR ARTICLE OF FLATWARE

Colin B. Richmond II, Newbury, Mass., assignor to
Charles D. Briddell Incorporated, Crisfield, Md., a
corporation of Maryland

Filed Feb. 2, 1965, Ser. No. 83,660

Term of patent 14 years

(Cl. D54—12)

Fig. 1

Fig. 2

Fig. 3

Fig. 4

Fig. 5

FIG. 1 is a front elevation of a spoon or similar article of flatware showing my new design;

FIG. 2 is a side elevation;

FIG. 3 is a rear elevation;

FIG. 4 is an enlarged transverse section taken on line 4—4 of FIG. 1; and

FIG. 5 is an enlarged transverse section taken on line 5—5 of FIG. 1.

The essential features of my design reside in the portions shown in full lines in the drawing.

I claim:

The ornamental design for a spoon or similar article of flatware, as shown and described.
